United States Patent Office

Des. 183,429
Patented Aug. 26, 1958

183,429

AUTOMOBILE DOOR HANDLE

Frederick Reynolds, Birmingham, Mich., assignor to Chrysler Corporation, Highland Park, Mich., a corporation of Delaware

Application July 29, 1957, Serial No. 47,120

Term of patent 14 years

(Cl. D10—8)

Fig. 1 is a side elevational view of an automobile door handle, showing my new design;

Fig. 2 is a section taken on the line 2—2 of Fig. 1;

Fig. 3 is a top plan view of the automobile door handle; and

Fig. 4 is an end elevation thereof.

I claim:

The ornamental design for an automobile door handle, substantially as shown.
